WIRE-TWISTER FOR BALING-MACHINES.

1,120,093.

Specification of Letters Patent.

Patented Dec. 8, 1914.

Application filed January 31, 1914. Serial No. 815,818.

To all whom it may concern:

Be it known that we, LEROY D. SHEELER and OLIVER G. SHAW, citizens of the United States, residing at Monroe, in the county of Jasper and State of Iowa, have invented a certain new and useful Wire-Twister for Baling-Machines, of which the following is a specification.

The object of our invention is to provide 10 a wire twisting device of simple, durable and inexpensive construction which is positive in action, and especially designed to be used in connection with an automatic hay tying press.

15 A further object is to provide an improved wire engaging and holding device to be used in connection with a rotary twisting member and so constructed that the wire will be positively held and twisted as the member is rotated.

20 Our invention consists in certain details, in the construction, arrangement and combination of the various parts of the device, whereby the objects contemplated are attained, as hereinafter more fully set forth, 25 pointed out in our claims and illustrated in the accompanying drawings, in which:

Figure 1 shows a cross sectional view of 30 a baling box in which our tying device is mounted. Fig. 2 shows a top view of the same. Fig. 3 shows a detail, side elevation of the tying member, and Fig. 4 is a detail view showing the manner in which the wires are supported and also showing the 35 position they take before the twisting operation commences.

Referring to the accompanying drawings, the reference numeral 10 indicates the top, 40 11 the bottom, and 12 the sides of an ordinary baling box. The top 10 is provided with a transverse member 13 and the bottom is provided with a similar transverse member 14. The ends of these members extend considerably beyond the side of the baling 45 box. The inner side of each of the members 13 and 14 is provided with a slot 15. Each of the sides 12 is provided with a vertical slot 16. This slot is designed to receive the wire moving mechanism, as will be herein- 50 after described.

The wire twisting devices are carried in a vertical frame member 17. This frame is composed of two bars spaced apart from each other, said frame being designed to 55 slide in the slots 15. Rotatably mounted in the frame 17 are two gear members 18 each

having a slot 19 extending from its periphery to its center. The center of said gear is provided with a hub 20, said hub being designed to rotate in the sides of the frame 17. 60 The frame 17 is provided with slots extending from one edge toward the center and is designed to be in line with the slot 19 when the slot 19 is in a horizontal position. A lever 21 is pivoted in the bottom of the slot 19, said lever being provided with laterally extending arms 22 near its pivoted end, the lever 21 being tapered toward its free end and designed to lie on the bottom of the slot 19 when in its normal position. When a 65 wire enters the slot 19 it will engage the upper one of the arms 22 and cause the free end of the lever 21 to be elevated so that when a second wire enters the groove 19 it will pass beneath the lever 21. This will 70 separate the two wires and at the same time prevent them from rotating relative to the gear member 18, as said gear is rotated. Thus it will be seen that as the gear 18 is rotated by means of the mechanism to be 75 hereinafter described, the wires within said gear will also be rotated.

For moving the wires into the slot 19, we have provided the following device: A bar 23 is slidably mounted in the grooves 15 80 and is designed to rest outside of the baling box when in its normal position. This bar 23 is provided with two notched arms 24. A vertical shaft 25 is rotatably mounted in the bars 13 and 14 and is provided with an arm 26 near its central portion, said arm being operatively connected with the bar 23 by means of a link 27. A shaft 28 is rotatably mounted in the opposite ends of the bars 13 and 14, from which the shaft 25 is mounted, 85 and is provided with two arms 29, said arms being operatively connected with the frame 17 by means of the links 30. The upper end of the shaft 28 is provided with a bell crank lever 31, one end of which forms a hand lever 32. An arm 33 is secured to the upper end of the shaft 25 and is connected to the bell crank lever 31 by means of a link 34. These shafts are so arranged that as the lever 32 is rotated in the direction indicated 90 by the arrow, the frame 17 and the bar 23 will be moved toward each other until the notches in the arms 24 are directly opposite the central portions of the gears 18. The gears 18 are operated by means of a gear 105 35, said gear being mounted upon the shaft 36 which extends through the frame mem-

bers 17 and has a beveled gear 37 on its outer end. The beveled gear 37 is in mesh with a beveled gear 38 mounted upon the horizontal shaft 39. This horizontal shaft 39 is secured to the frame 17 by means of the brackets 40 and has a crank 41 on its free end by which said shaft may be rotated.

To prevent the gears 18 from rotating 10 when the crank 41 is not being operated, and to keep the slots 19 in a horizontal position, we have provided a pawl 41^a pivoted to the side of the frame 17 and having its hooked portion held in engagement with the teeth of 15 the gear 35 by means of a spring 42^a. When it is desired to rotate the gears 18, the pawl 41^a is first moved out of engagement with the gear 35.

For severing the wires after they have 20 been twisted, we have provided a pair of shears 42 secured to one side of the frame 17 and adjacent to each of the slots 20. These shears are operated by means of a lever 43 and the links 44, the lever 43 being pivoted 25 at its central portion to the frame 17 by means of the pivot 45. The shears 42 and the wire threading device form no part of our present invention and are only shown and described to make the wire twisting 30 mechanism operative.

In practical operation, the levers 32 and 43 and the crank 41 will be operated automatically by some mechanism from the baling press.

35 On each side of the baling box, two sets of wires 46 are provided and those on the left side are in line with the notches in the arms 24. Those on the right hand side of the box are in line with the grooves 19. It will be 40 seen that as the lever 32 is operated, the bar 23 and the frame 17 will be moved toward each other in the slots 15 which will cause the wires on the right hand side of the machine to enter the groove 19 and pass 45 over the top of the lever 21, thereby causing said lever to move to the top of the groove 19. As the frames are advanced, the wire on the left hand side of the machine will be moved toward the frame 17 and will 50 also enter the groove 19 and pass beneath the lever 21, at which time the wires 46 will be at the central portion of the baling box, as illustrated in Fig. 4. As the crank 41 is 55 operated, the gear 35 will be rotated and with it the gears 18 which will cause the two wires to be twisted around each other, after which the lever 43 may be operated and the twisted portion of the wire severed.

Thus it will be seen that as the gears 18 are rotated on account of the lever 21 being between the wires within said gear, it will be impossible for the wires to rotate relative to the said gears.

It is to be understood that this device may be used in connection with any wire twisting device which has a rotary twisting member and slot similar to the one in the gears 18.

There are a number of hay balers using a wire twisting device which employs a rotary 70 gear and a radial slot, the width of the slot in these cases being practically the same as the diameter of the wire used. After the wire twister has been used for some time, the slots will become worn and permit the 75 wires to rotate within them. It is also difficult to twist more than one sized wire. These objections we have overcome by employing the lever 21.

We claim as our invention:

1. In a wire twister, the combination of a rotatable member having a slot therein to receive wires, and a pivoted lever within the slot, said lever being formed with wire engaging arms at its side edges, for the purposes stated.

2. In a wire twister, the combination of a rotatable wheel having a slot therein to receive wires, a lever pivoted within the wheel with its free end in said slot, said lever being provided with arms at each edge, and means for rotating the wheel.

3. In a wire twister, the combination of a rotatable member having a slot extending to its central portion, a pivoted lever in said slot, said lever having opposite arms whereby the lever is automatically moved by wires toward the side of the slot on which the wire engages the lever so that when two wires are successively placed in the slot they 100 will always stand on opposite sides of the lever.

4. In a wire twister, the combination of a rotatable wheel having a slot therein to receive wires, a lever pivoted within the wheel 105 with its free end in said slot, said lever being provided with arms at each edge, means for rotating the wheel, and means for locking the wheel against rotation.

Des Moines, Iowa, July 31, 1913.
